UNITED STATES PATENT OFFICE.

JOHN D. BEERS, OF PHILADELPHIA, PENNSYLVANIA.

IMPROVEMENT IN STEAM-GENERATORS.

Specification forming part of Letters Patent No. 146,506, dated January 20, 1874; application filed September 4, 1873.

To all whom it may concern:

Be it known that I, JOHN D. BEERS, of the city of Philadelphia and State of Pennsylvania, have invented certain Improvements in Steam-Generators, of which the following is a specification:

My invention relates to that class of steam-generators which have vertical circulating water-tubes in the fire-box, and whose lower ends connect with the side water-spaces around the fire-box, and their upper ends with the upper water-space which connects with the side water-spaces. The invention consists of a series of tubes, which are arranged horizontally in the upper part of the upper water-space, and connect at each end with the smoke-space, whereby the heat is imparted from the smoke to the steam in the upper part of said water-space, as hereinafter described.

Figure 1 is a front elevation of my improved generator. Fig. 2 is a side elevation of the same. Fig. 3 is a cross-section at the line *x x* of Fig. 1. Fig. 4 is a like view at the line *y y* of Fig. 1.

Like letters of reference in all the figures indicate the same parts.

A is the fire-box. B B B B and B' represent the water-spaces between the vertical side plates *a a a a* and head-plate *a'* of the fire-box, and the vertical side plates *b b b b* and crown-plate *b'* of the water-jacket C. D is the fire-place, above which a series of tubes, *c*, are arranged. The lower ends of the tubes are bent as represented in Fig. 1, right and left, and form a series of arches, against which the heat strikes as it ascends, whereby it is retained much longer on the tubes than otherwise, for its more complete utilization. The bent ends of the tubes connect with the plates *a a* of the fire-box, and communicate with the water-spaces B B. Their upper ends connect with the head-plate *a'*, and communicate with the water-space B'. There are openings E E communicating with the water-spaces B B opposite the bent ends of the tubes *c*, to provide for the connecting of the tubes, cleaning them out, &c. They are covered by means of the plates F F, which are confined with screw-

bolts *d*. In Fig. 2 a plate, F, is removed to show the connection of one set of the tubes with the plates *a* of the fire-box.

As the water is heated in the tubes *c* it rises to the upper end of the same into the water-space B', as the colder and consequently heavier water in the spaces B descends and enters the lower ends of the tubes. The water in the upper ends, as it becomes sufficiently charged with heat, generates steam, which occupies that part of the space B above the water-line *e*. Hence a continuous circuit is made and kept up, the colder water in the side water-spaces descending into the tube and pushing the heated water therein upward, which, in its ascent, accumulates additional heat, and is converted into steam, and by means of a pipe or pipes, (not shown,) in the drawings, is carried to the engine.

G is a cap, which is provided with flanges *f f*, that are bolted fast to the flanges *f' f'* of the side plates *b b* of the water-jacket, whereby the smoke-chamber H is formed around and over the crown-plate *b'* of the water-space B'. The smoke is brought from immediately under the top plate *a'* of the fire-box, through tubes *g*, into the smoke-chamber H at two opposite sides of the fire-box. The tubes pass through the water-spaces B B, either end being confined in the side plates of the fire-box and water-jacket.

The smoke passes through the smoke-chamber, as indicated by the arrows, to the exit-pipe I. In passing over the crown-plate *b'* of the water-jacket, a considerable portion of its heat is transmitted to the crown-plate, which is radiated from its inner surface upon the steam in the upper part of the water-space B' above the water-line *e*.

I claim as my invention—

The combination and arrangement of the series of tubes *g* with the upper water-space B and the smoke-chamber H, substantially as and for the purpose set forth.

JOHN D. BEERS.
